CLAMP-AROUND VOLT-AMMETER

Harvey A. Schwartz, Merrick, N.Y., assignor to Soss
Manufacturing Company, Detroit, Mich., a cor-
poration of Nevada

Filed July 11, 1967, Ser. No. 7,763

Term of patent 14 years

(Cl. D26—1)

FIG. 1 is a front view of a clamp-around volt-ammeter showing my new design.

FIG. 2 is a side view thereof.

FIG. 3 is a rear view thereof.

FIG. 4 is a side view opposite that of FIG. 2.

FIG. 5 is a top view thereof.

FIG. 6 is a bottom view thereof.

The dominant features of the design reside in the full line portions of the drawing.

I claim:

The ornamental design for a clamp-around volt-ammeter, substantially as shown and described.
